UNITED STATES PATENT OFFICE.

WALTER L. WILKS, OF BRIDGEPORT, CONNECTICUT, ASSIGNOR TO THE HOLMES & EDWARDS SILVER COMPANY, OF SAME PLACE.

DESIGN FOR A SPOON.

SPECIFICATION forming part of Design No. 20,510, dated February 10, 1891.

Application filed December 15, 1890. Serial No. 374,815. Term of patent 14 years.

To all whom it may concern:

Be it known that I, WALTER L. WILKS, a citizen of the United States, residing at Bridgeport, Fairfield county, Connecticut, have invented a new and useful Design for Spoons, of which the following is a specification.

Figure 1 is a face view of a sugar-spoon, showing my design; and Fig. 2 is a reverse view.

The handle of the spoon has a swell *x* between the end and the contracted portion *y* of the shank, and upon this wider portion *x* is a panel *a*, above which is a series of figures constituting a foliated or arabesque ornamentation, as shown, and upon the stem below the panel are other curved figures, also constituting a foliated or arabesque ornamentation, as shown, the said figures being carried to the back or reverse side of the handle in the form of a light open vine or foliated ornamentation, as shown.

The bowl of the spoon is ornamented at the upper edge with two lateral rounded exten-

sions *b b*, upon which are scroll-like ornaments, and from the scrolls radiate plume-like ornaments *e e e e*.

What I claim is—

1. The design for a spoon herein shown and described, the same comprising the foliated ornamentation upon the face of the handle, 30 as shown.
2. The design for a spoon herein shown and described, the same comprising the foliated ornamentation upon the reverse side of the handle, as shown.

3. The design for a spoon herein shown and described, the same comprising the bowl with lateral projections *b b* and scrolls and radiating plumes *e*, as shown.

In testimony whereof I have signed my name 40 to this specification in the presence of two subscribing witnesses.

WALTER L. WILKS.
